DESIGN FOR A COMBINED BOTTLE AND STOPPER

Paul H. Ganz, New York, N. Y., assignor to Prince Matchabelli Perfumery, Inc., New York,
N. Y., a corporation of New York

Application April 27, 1937, Serial No. 69,000

Term of patent 14 years

To all whom it may concern:

Be it known that I, Paul H. Ganz, a citizen of the United States and a resident of the city, county, and State of New York, have invented a new, original, and ornamental Design for a Combined Bottle and Stopper, of which the following is a specification, reference being had to the accompanying drawing, forming part thereof.

Figure 1 is a front elevational view of a combined bottle and stopper showing my new design;
Figure 2 is an end view thereof; and Figure 3 is a plan view thereof.

I claim:

The ornamental design for a combined bottle and stopper as shown and described.

PAUL H. GANZ.
